(57) **CLAIM**

The ornamental design for a chair, as shown and described.

DESCRIPTION

FIG. 1 is a front perspective view of a chair showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view of a second embodiment of a chair showing the new design;

FIG. 10 is a rear perspective view of the chair shown in FIG. 9;

FIG. 11 is a front view of the chair shown in FIG. 9;

FIG. 12 is a rear view of the chair shown in FIG. 9;

FIG. 13 is a right side view of the chair shown in FIG. 9;

FIG. 14 is a left side view of the chair shown in FIG. 9;

FIG. 15 is a top view of the chair shown in FIG. 9; and,

FIG. 16 is a bottom view of the chair shown in FIG. 9.

The broken lines illustrate portions of the chair that form no part of the claimed design.

1 Claim, 16 Drawing Sheets
